Primary Examiner — Kimberly Barnes

(57) **CLAIM**

The ornamental design for an automatic swimming pool cleaner as shown and described.

DESCRIPTION

1.1 is a front view of an automatic swimming pool cleaner showing my new design;

1.2 is a back view thereof;

1.3 is a left view thereof;

1.4 is a right view thereof;

1.5 is a top view thereof;

1.6 is a bottom view thereof;

1.7 is a top front perspective view thereof;

1.8 is a bottom perspective view thereof;

1.9 is a top back perspective view thereof.

The broken lines in the drawings are for illustrative purposes only and form no part of the claimed design.

1 Claim, 9 Drawing Sheets
